(57) **CLAIM**

The ornamental design for a combined container for fluids with cap as shown and described.

DESCRIPTION

1. Combined container for fluids with cap
1.1 is a bottom plan view of a combined container for fluids with cap showing our new design;
1.2 is a front side elevation view thereof;
1.3 is a rear side elevation view thereof;
1.4 is a perspective view thereof;
1.5 is a right side elevation view thereof;
1.6 is a left side elevation view thereof; and
1.7 is a top plan view thereof.

The design shows a combined container for fluids with cap, namely ink or solvent for an inkjet printer. The dash-dot broken lines are directed to environment, are for illustrative purposes only, and form no part of the claimed design. The dash-dash broken lines represent the bounds of the claimed design and form no part of the claimed design

1 Claim, 7 Drawing Sheets
